UNITED STATES PATENT OFFICE

119,548

DESIGN FOR AN ELASTIC FABRIC

Eugene Franklin Gaines, deceased, late of Bala,
Pa., by Jean S. Gaines, administratrix, Nar-
berth, Pa.

Application September 6, 1939, Serial No. 87,063

Term of patent 14 years

To all whom it may concern:

Be it known that I, Jean S. Gaines, a citizen of the United States of America, residing at Narberth, in the county of Montgomery and State of Pennsylvania, administratrix of the estate of Eugene Franklin Gaines, deceased, late a citizen of the United States of America and a resident of Bala, in the county of Montgomery and State of Pennsylvania, do hereby declare that he invented a new, original, and ornamental Design for an Elastic Fabric, of which the following is a specification, reference being had to the accompanying drawing, forming part thereof.

Fig. I is a front view of an elastic fabric embodying the ornamental design of this invention, to which no tension is applied.

Fig. II is a view of the elastic fabric depicted in Fig. I, as it appears when subjected to approximately 100% stretch longitudinally of the fabric; and

Fig. III is a view of the fabric in Fig. I as it appears when subjected to substantial stretching transversely of the fabric.

The figures disclose the elastic fabric enlarged approximately 1½ times normal size so that they will be approximately full size upon reduction of the same to the ultimate size as appears in the patent copy.

The reverse side of the fabric has substantially the same appearance as the front side shown in the several figures.

I claim:

The ornamental design for an elastic fabric, as shown and described.

JEAN S. GAINES,
Administratrix of the Estate of Eugene Franklin Gaines, Deceased.
